Primary Examiner — Patricia A Palasik(74) *Attorney, Agent, or Firm* — Maschoff Brennan(57) **CLAIM**

The ornamental design for a mechanism for various object re-orientation and alignment, as shown and described.

DESCRIPTION

FIG. 1 is a front view of a mechanism for various object re-orientation and alignment, showing my new design;

FIG. 2 is a back view thereof;

FIG. 3 is a top view thereof;

FIG. 4 is a bottom view thereof;

FIG. 5 is a top, front, and left side perspective view thereof;

FIG. 6 is a top, front, and right side perspective view thereof;

FIG. 7 is a left view thereof; and,

FIG. 8 is a right view thereof.

The broken lines in the figures illustrate the portions of the design that form no part of the claimed design.
